TENBORG, SWEDEN, A CORPORATION OF SWEDEN.

DEVICE FOR MAINTAINING THE WORKING SURFACE OF THE GRINDING DISK IN
GRINDING MACHINES.

Application filed July 29, 1921, Serial No. 488,273, and in Sweden August 21, 1920.

The present invention relates to a device for maintaining the form and position of the working surface of the grinding disk in grinding machines. The object of the invention is to enable the operator to determine the moment when the working surface of the grinding disk takes up a predetermined position, to maintain it in such position and to maintain the form of the working surface of the grinding disk. The invention consists, essentially, in the grinding machine being provided with a feed device for the grinding disk, said feed device working continuously or at definite intervals, and also with a rotary dressing or abrading member for the working surface of the grinding disk. The working surface of the dressing member, or the part thereof engaging the working surface of the grinding disk, is suitably maintained in a predetermined position dependent on the final form, or dimensions, of the work piece to be ground, so that it will be possible to decide, by the formation of sparks between the working surfaces of the dressing member and the grinding disk, when the said surfaces enter into engagement, i. e. the moment when the working surface of the grinding disk takes up the desired position. The continuous or intermittent feeding of the grinding disk, which shall be regulable in amount, should be chosen so as to be greater than the wear of the grinding disk caused by the work piece alone but equal or substantially equal to the wear caused by the dressing member and the work piece jointly, so that an effective grinding is obtained and the pressure between the grinding disk and the dressing member will not be too great. The shape of the working surface of the dressing member is dependent on that of the working surface of the grinding disk.

The invention is illustrated schematically in the annexed drawing. Fig. 1 is a longitudinal section of a device according to this invention. Fig. 2 is a cross-section on line A—B of Fig. 1. Figs. 3 and 4 show an application of the device in grinding gear wheels.

50 Referring to Figs. 1 and 2, 1 designates a frame on which a slide 2 is movable, said slide forming a bearing for the grinding disk

3 driven by the pulley 4. The movement of the slide 2, i. e. the feeding of the grinding disk 3 in a direction towards the work piece 5 is effected by a screw 6 journaled in the frame 1, said screw being driven by a worm wheel 7 engaged by a worm 8. Attached to the worm 8, which is journaled in the frame in suitable manner, is a second worm wheel 9 engaged by a worm 10 likewise journaled in the frame 1 and firmly connected to a friction disk 11. Journaled in the upper part of the frame 1 is, further, a second friction disk 12 carrying a belt pulley; and mounted between the friction disks 11 and 12 is a radially adjustable friction roller 13 by which the ratio of gearing between the disks 11 and 12 can be varied. If the friction disk 12 is rotated, the friction disk 11 will, obviously, also rotate, through the medium of the roller 13, and so will also the screw 6, through the medium of the worm gears 7, 8 and 9, 10. On account thereof, the slide 2 and, thereby, the grinding disk 3 will be moved towards the work piece 5 with a speed which, on account of the chosen elements of translation (worm gears), will be very small and, by suitably adjusting the friction roller 13, can be made slightly greater than the wear of the grinding disk caused by the work piece 5, the pressure between the grinding disk and the work piece being easily determined with regard to the formation of sparks. Longitudinally movably but non-rotatably mounted on the shaft 14 is, further, a dressing or abrading member 15 the working surface 16 of which, in the form of embodiment shown, is annular in shape, and plane. The dressing member 15 is kept pressed, by a spring 17 placed around the shaft 14, against contact devices illustrated in the form of rollers 18 rotatably journaled in a slide 19 adjustably mounted in the frame 1 and secured in place by some suitable means, as a screw 19^a as shown. Said slide serves at the same time as a bearing for the shaft 14, through the medium of a sleeve-like prolongation 20 of the member 15. The position of the working surface 16 of the member 15 is thus fully determined by the rollers 18, and by adjusting the slide 19 with the rollers 18 in such manner that the tangent plane of the rollers (corresponding to

line A—B of Fig. 1) is at a distance from the axial line 21 of the work piece 5, which is equal to the final desired radius of the work piece 5 or, generally, corresponds to a desired dimension, it is, thus, possible to decide when this dimension has been attained, inasmuch as parts 3 and 15 will then so come in contact as to form sparks between them. The fact that the member 15 can also be worn is, obviously, insignificant, since, through the action of the spring 17, the position of its working surface 16 is fully determined by the rollers 18. By so choosing the feed of the grinding disk that, as hereinbefore mentioned, it will be equal or substantially equal to the wear of the grinding disk caused by the work piece and the dressing member jointly, the working surface of the grinding disk will, obviously, always take up the position determined by the dressing member, or the rollers 18, and, through the action of the rotary dressing member, maintain its plane form. These circumstances, viz the maintaining of the working surface of the grinding disk in a fixed position and the maintaining of the plane form of its working surface, are known to be of considerable importance, especially in grinding tooth profiles according to the rolling principle, the working surface then representing a tooth side or part thereof in a theoretical or imagined generating rack, or an imagined generating wheel, the position and form of which are not allowed to be changed.

In Figs. 3 and 4, an application of the arrangement for grinding gear wheels according to the rolling principle is schematically illustrated, 3 designating, as in Figs. 1 and 2, the grinding disk fed with the speed hereinbefore mentioned, said disk having here the shape of a plate, and 15 designating the rotary dressing or abrading member fixed in position. The working surface 22 of the grinding disk, the position of which is fully determined, as hereinbefore mentioned, by the working surface 16 of the dressing member, represents a tooth side in an imagined generating rack 23. It is essential to maintain the form of the working surface of the grinding disk, which, in the illustrated form, is plane.

In both forms shown in the drawings the peripheral speed is greater at the outer circumference of the annular working surface 22 than at the inner circumference, the wear of the grinding disk, in grinding certain forms as for instance a tooth profile, would, if no measures to the contrary were taken, be greater at the outer circumference than at the inner circumference, i. e. the working surface of the grinding disk would not maintain its plane form but would obtain a curved profile. The dressing or abrading member 15 is, therefore, to be arranged in

such manner as to exert a greater abrading action at the inner circumference of the surface 22 of the grinding disk than at the outer circumference. This can be attained by the working surface 16 of the dressing member being annular in shape, as shown, and by the same being placed in such manner relatively to the working surface 22 of the grinding disk that, as clearly shown in Fig. 4, the engagement of each element of said surfaces 16 and 22 takes place during a longer time at and near the inner circumference of the surface 22 of the grinding disk than at the outer circumference.

While the working surface of the grinding disk in relation to that of the dressing member is such as shown in Figs. 3 and 4 as to exert a greater abrading action at the inner circumference of the surface of the grinding disk than at the outer circumference as above explained, it is obvious that the corresponding parts shown in Figs. 1 and 2 may be similarly disposed to bring about this action, no change in the construction of the parts being necessary other than an increase of the inner diameter of the grinding surface 22 to cause said surface to occupy the same relation to the surface 16 as is shown in Fig. 3.

The working surface of the dressing member need not be plane since it is, obviously, dependent on the form to be given to the working surfaces of the grinding disk. It is also obvious that if desired, the feed of the grinding disk need not be continuous.

I claim:

1. An arrangement for maintaining the form and position of the working surface of the grinding disk in grinding machines, characterized by an annular grinding disk, a feed device for the grinding disk and by a rotary annular dressing or abrading member with which the annular working surface of the grinding disk is maintained in engagement.

2. An arrangement according to claim 1, characterized by the grinding disk being automatically feed forward more than the wear of the grinding disk caused by the work piece alone but equal or substantially equal to the wear caused by the work piece and the dressing or abrading member jointly.

3. An arrangement according to claim 1, characterized by means for limiting the inward movement of the dressing or abrading member for fixing its working face in a certain predetermined position.

4. An arrangement according to claim 1, characterized by the working surface of the dressing or abrading member being plane.

5. An arrangement according to claim 1, characterized by the dressing or abrading member being so arranged relatively to the grinding disk as to exert a less abrading action at and near the outer circumference of

the grinding disk than at places located nearer to the axis of rotation of the grinding disk.

6. An arrangement according to claim 1, characterized by the working surface of the dressing or abrading member being kept pressed, through the action of a spring or the like, against an adjustable device consisting, suitably, of rollers rotatably journaled in an adjustable slide or the like, whereby the working surface of the dressing members is held in a fixed predetermined position so far as inward movement is concerned.
- 10 7. In a mechanism of the type described, the combination of a rotary grinding member, a rotary dressing member adapted to act on the working surface of the grinding member, a contact device normally in engagement with the working surface of the dressing member and adjustable to position said surface at a predetermined relation to the final surface of the work to be ground, means for maintaining the engagement of 25 the working surface of the dressing member with said contact device, and means for feeding the grinding member to engage the working surface of the dressing member and to act on the work.
- 30 8. In a mechanism of the type described, the combination of a rotary grinding member, a rotary dressing member adapted to act on the working surface of the grinding member, a series of contact rollers normally 35 in engagement with the working surface of the dressing member and adjustable to position said surface at a predetermined relation to the final surface of the work to be ground, means for maintaining the engagement of 40 the working surface of the dressing member with said contact rollers, and means for feeding the grinding member to engage the working surface of the dressing member and to act on the work.
- 45 9. In a mechanism of the type described, the combination of a rotary grinding member, a rotary dressing member adapted to act on the working surface of the grinding member, a contact device engaged by the 50 working surface of the dressing member and

adjustable to position said surface at a predetermined relation to the final surface of the work to be ground, means for yieldingly maintaining the engagement of the working surface of the dressing member with 55 said contact device, and means for feeding the grinding member to engage the working surface of the dressing member and to act on the work.

10. In a mechanism of the type described, 60 the combination of a rotary grinding member, a rotary dressing member adapted to act on the working surface of the grinding member, a series of contact rollers engaged by the working surface of the dressing member and adjustable to position said surface at a predetermined relation to the final surface of the work to be ground, means for yieldingly maintaining the engagement of 65 the dressing member with said contact 70 rollers, and means for feeding the grinding member to engage the working surface of the dressing member and to act on the work.

11. The combination of a rotary grinder 75 of annular form, a rotary dressing member of annular form adapted to engage the working surface of the grinder, and a series of rollers engaging the working surface of the dressing member for determining the position of the working surface of the grinder, 80 the organization of the parts being such that the working surfaces of the grinder and of the dressing member are disposed in the same plane when in working relation.

12. The combination of a rotary grinder 85 of annular form, a rotary dressing member of annular form adapted to engage the working surface of the grinder, a series of rollers engaging the working surface of the dressing member for determining the position of the working surface of the grinder, 90 the organization of the parts being such that the working surfaces of the grinder and of the dressing member are disposed in the same plane when in working relation, and 95 means for shifting said rollers for adjusting the position of the said plane.

In testimony whereof I have signed my name.

AXEL FREDRIK THURE LÖFQUIST.
